(57) **CLAIM**

The ornamental design for a security tag design, as shown and described.

DESCRIPTION

FIG. 1 is a top perspective view illustrating my design for a security tag design;

FIG. 2 is a top view thereof;

FIG. 3 is a left side view thereof;

FIG. 4 is a rear view thereof;

FIG. 5 is a right side view thereof;

FIG. 6 is a front view thereof;

FIG. 7 is a bottom view thereof

FIG. 8 is a bottom perspective view thereof; and,

FIG. 9 is a top perspective view thereof.

In the drawings, the broken line showing of a security tag cap depicts environmental subject matter and forms no part of the claim.

1 Claim, 5 Drawing Sheets
